UNITED STATES PATENT OFFICE.

EDWARD W. STEVENS, OF DETROIT, MICHIGAN, ASSIGNOR OF ONE-HALF TO CHARLES E. STEVENS, OF CHICAGO, ILLINOIS.

PNEUMATIC-TIRE DEFLATOR.

1,256,388.

Specification of Letters Patent. Patented Feb. 12, 1918.

Application filed October 9, 1916. Serial No. 124,537.

To all whom it may concern:

Be it known that I, EDWARD W. STEVENS, a citizen of the United States, residing at Detroit, in the county of Wayne and State 5 of Michigan, have invented a certain new and useful Improvement in Pneumatic-Tire Deflators, of which the following is a full, clear, concise, and exact description, reference being had to the accompanying drawings, forming a part of this specification.

This invention relates to pneumatic tire deflators, and has as its object the production of a simple and inexpensive device of this character which may be inserted into 15 the interior of the valve casing to engage the valve stem and unseat the valve. The device is designed to permit the ends thereof to be compressed or brought together and inserted into the valve casing when in this condition, 20 and to expand and engage the inner wall of the casing, and be held in position therein, when the pressure which brought them together is released.

When the device is in said last named position, the valve is held away from its seat, which permits the air to escape and consequently deflates the tire.

The device will be more readily understood with reference to the accompanying 30 drawing, in which Figure 1 is a perspective view thereof;

Fig. 2 shows a valve casing in section, the device applied thereto and engaging the stem of the valve, holding the same away 35 from its seat;

Fig. 3 is a view of a blank from which the device is formed.

The device is preferably formed of a small strip of spring steel or the like. This 40 strip is bent upon itself to provide the arms 10 and 11 and the bowspring portion 12, which normally holds said arms in extended position. These arms 10 and 11 are constructed so that they will be of sufficient 45 strength to prevent bending thereof, due to the resistance of the spring 12 while the same is being overcome and the arms are being brought together. To provide for this desired degree of strength each of said 50 arms is provided with a reinforcing rib 13, which extends substantially from the lowermost portion of each of said arms to a short distance beyond where the spring portion

begins, thus the possibility of crystallization and consequent weakening of the device at this point is eliminated. The spring portion 12 is formed of the material of which the arms are formed, and is preferably bent to result in the bowspring 12. This spring portion 12 may be provided with 55 an eyelet 14 which is bent up from the portion which forms the spring, for the purpose of affording a means whereby the device may be attached to a key ring, or for the attachment of a plate upon which an advertisement may be inscribed. The lowermost portion of each of the arms is provided with a laterally extending lug 15 which when the arms 10 and 11 are expanded engage the internal threads of the valve casing 16. These 60 lugs are preferably formed or bent from the same metal which forms the arms 10 and 11, and have their outer edges shaped to conform to the interior of the valve casing. One of the arms 10 or 11 is provided with a 65 projecting tongue 17 which may be punched therefrom and bent inwardly, and is for the purpose of engaging the uppermost portion of the valve stem to hold the valve away 70 from its seat to permit air to escape from the tire which has previously been inflated, when the device has been inserted into the valve casing. 75

The device eliminates the necessity of requiring the user to give his entire attention to the deflation of the tire by requiring him to hold the valve down and away from its seat, and permits him to utilize this time in some other manner. When the device is desired to be inserted in the valve casing 80 85 18 to deflate a tire, the arms 10 and 11 will be compressed and inserted into the valve casing 18 to the desired extent. This will cause the tongue 17 to engage the valve stem 19 and unseat the valve 20. The arms will 90 then be released and expanded by the action of the bowspring 12. This causes the engagement of the lugs 14 with the internal threads 16 of the valve casing, which holds the device in position, resists the valve 95 100 spring 22, holds the valve 20 away from its seat, and permits the tire to be deflated.

It will be understood that changes and modifications may be made without departing from the spirit of the invention.

Having thus described my invention, what

I claim as new and desire to secure by Letters Patent is:

1. In a device of the class described, the combination of a pair of normally expanded arms, spring means for expanding said arms, an outwardly extending lug provided upon each of said arms and an inwardly extending tongue extending between said arms.
2. In a device of the class described, the combination of a pair of normally expanded arms, spring means for expanding said arms, said means connecting said arms, an outwardly extending lug provided upon each of said arms and an inwardly projecting tongue extending between said arms.
3. In a device of the character described, the combination of a pair of connected spring actuated normally extended arms, each of said arms having an outwardly extending lug and one of said arms being provided with an inwardly projecting tongue which extends between said arms.
4. A device of the class described, being formed of a single strip of metal, which is bent substantially U-shape, the ends thereof being bent outwardly to form holding lugs, that portion of said strip at the bend of the U forming a spring whereby the arms are

normally held extended, and one of said arms having a lug punched therefrom and bent inwardly to extend between the arms.

5. In a device of the class described, the combination with a pair of arms, integral spring means arranged between said arms, a lug provided upon each of said arms, a member arranged between said arms and a rib extending from said lug of each arm to the above mentioned spring means.

6. In a device of the class described, the combination of a pair of arms, means for expanding said arms, an outwardly extending lug provided upon each of said arms, an inwardly extending member extending between said arms, and means provided in the means for expanding the arms whereby the device may be secured to another member, said means including a downwardly extending strap punched from the material of which the arm expanding member is formed.

In witness whereof, I hereunto subscribe my name this 2nd day of Oct., A. D. 1916.

EDWARD W. STEVENS.
